UNITED STATES PATENT OFFICE

117,071

DESIGN FOR A SWING SPOUT FAUCET

Robert Douglas McIntosh, River Forest, Ill., assignor to The Imperial Brass Manufacturing Company, Chicago, Ill., a corporation of Illinois

Application March 13, 1939, Serial No. 83,532

Term of patent 7 years

To all whom it may concern:

Be it known that I, Robert Douglas McIntosh, a citizen of the United States and a resident of River Forest, in the county of Cook and State of Illinois, have invented a new, original, and ornamental Design for a Swing Spout Faucet, of which the following is a specification, reference being had to the accompanying drawing, forming part thereof.

I claim:

The ornamental design for a swing spout faucet, substantially as shown.

ROBERT DOUGLAS McINTOSH.
